UNITED STATES PATENT OFFICE.

HOWARD A. HANDS, OF SWISSVALE, PENNSYLVANIA, ASSIGNOR TO WESTINGHOUSE ELECTRIC & MANUFACTURING COMPANY, A CORPORATION OF PENNSYLVANIA.

RESISTOR-SUPPORTING MEANS FOR ELECTRIC RESISTANCE FURNACES.

Application filed January 20, 1922. Serial No. 530,558.

To all whom it may concern:

Be it known that I, HOWARD A. HANDS, a citizen of the United States, and a resident of Swissvale, in the county of Allegheny and State of Pennsylvania, have invented a new and useful Improvement in Resistor-Supporting Means for Electric Resistance Furnaces, of which the following is a specification.

10 My invention relates to electric furnaces and particularly to electric-resistance furnaces, and it has for its object to provide a relatively simple, inexpensive, and easily assembled and disassembled heating element for an electric-resistance furnace.

In practising my invention, I provide a plurality of sets of relatively narrow members of substantially T-shape having one or more overhanging flange portions at one end thereof, each of said flange portions having a depression therein. I provide a metallic supporting member or stirrup, substantially rectangular in form, which is supported by the overhanging flange portions of the refractory resistor-supporting member and, in turn, supports a relatively heavy resistor rod or bar.

In the single sheet of drawings,

Figure 1 is a view, in vertical lateral cross-section, of an electric-resistance furnace in which is incorporated the device embodying my invention;

Fig. 2 is a view, in side elevation, of a plurality of refractory supporting members, stirrups and a resistor member, illustrated in substantially the positions occupied in the furnace structure.

Fig. 3 is a view, in end elevation, of a stirrup, together with a resistor member supported thereby;

Fig. 4 is a view, in side elevation, of a modified form of refractory resistor-supporting member, and

Fig. 5 is a lateral cross-sectional view thereof on the line V—V of Fig. 4.

A furnace, designated generally by the numeral 11, comprises an outer metallic framework or skeleton 12 having a plurality of supporting members 13 suitably secured thereto. An outer lining 14 comprises a plurality of bricks or blocks of any suitable heat-insulating material. An inner lining 15 comprises a plurality of bricks or blocks of any suitable high-temperature-resisting refractory material, the bricks comprising

the two linings being so formed and disposed as to provide a furnace chamber 16 of any suitable or desired contour and dimensions.

A plurality of spaced sets of relatively narrow spaced-apart refractory members 17, of substantially T-shape, are supported in any suitable or convenient manner by the inner lining 15, more particularly by the extended flanges of the outer ends thereof. The inner end of each of the members 17, extending into the furnace chamber 16, which may be of arcuate contour, is provided with a laterally-extending slot 18 adjacent thereto. The slots 18 have an inner widened portion for a purpose to be hereinafter set forth in detail. A metallic resistor-supporting member or stirrup 19 comprises a relatively narrow strip of metal bent to substantially box form or of rectangular contour. The width of the strip constituting the stirrup 19 is such as to fit into the deeper portion of the slot 18 in the member 17. The outer flange portion 21 prevents any movement of the member 19 relative to the member 17.

A resistor member 22 comprises a relatively heavy rod, bar or strip of any suitable resistance material of a width to fit into, and be supported by, the stirrup 19, substantially as illustrated in Fig. 3 of the drawing. The area of lateral cross section of the resistor 22 is such as to make the resistor substantially self-supporting between the spaced-apart refractory supporting members 17. While no method is illustrated of connecting the individual resistor bars 22, any means in the art may be employed or the adjacent and substantially parallel-extending convolutions 22 may be made integral by preforming the resistor member before placing it in its proper operative position in the furnace chamber. If it is desired to place the heating element in its proper operative position in the furnace by movement of the resistor bars 22 longitudinally of their length, it has been found easier to make the bars 22 each substantially as long as the furnace chamber and then to connect the same by suitable cross-connecting members (not shown).

My invention has particular reference to means for supporting a resistor member from the roof of the furnace, but, if desired, members 17 may be employed in the side

walls of the furnace, and the metallic supporting member 19 be dispensed with, the resistor bar 22 being placed in the slot 18, substantially as illustrated in Fig. 1 of the drawing.

Figs. 4 and 5 illustrate a modified form of the refractory resistor supporting member. A refractory member 23, substantially of T-shape, is provided with two parallel-extending slots or grooves 24 in opposite faces, adjacent the inner end thereof, thus providing two overhanging flanges upon which a metallic supporting member or stirrup 19 may be mounted. A centrally located depression 25 is provided in each of the overhanging flange portions of the members 23 within which the stirrup 19 may be located to prevent movement of the member 19 longitudinally of the resistor bar 22 which as is well known, may expand and contract longitudinally of its length during the operation of the furnace.

Various modifications may be made in the device embodying my invention without departing from the spirit and scope thereof and I desire that only such limitations shall be placed thereon as are imposed by the prior art or are specifically set forth in the appended claims.

30 I claim as my invention:—

1. In an electric furnace, in combination, a plurality of relatively narrow refractory members, of substantially T-shape, each having a projecting portion provided with an overhanging flange, stirrups supported by said overhanging flanges and a resistor member supported by said stirrups.

2. In an electric furnace, in combination, a plurality of relatively narrow refractory members, of substantially T-shape, each having an overhanging flange portion, stirrups supported by said overhanging flange portions, embodying means in said flange portions for holding said stirrups in proper operative position, and a resistor member supported by said stirrups.

3. In an electric furnace, in combination, a plurality of spaced sets of spaced-apart,

relatively narrow refractory members, each member having an overhanging flange portion, stirrups supported by said overhanging flange portions, embodying means in said flange portions for holding said stirrups in their proper operative positions, and a relatively heavy resistor member supported at spaced intervals by said stirrups and being self-supporting therebetween.

4. In an electric furnace, in combination, a plurality of refractory walls enclosing a furnace chamber, a plurality of spaced sets of spaced-apart relatively narrow refractory members supported by one of said walls, each of said refractory members having a portion projecting into said chamber, said portion being provided with an overhanging flange portion, stirrups supported by the flange portion of the respective refractory members, a relatively heavy resistor member supported at spaced intervals by said stirrups and being self-supporting therebetween, and embodying means in said flange portions for preventing movement of said stirrups longitudinally of said resistor member when the same expands and contracts during operation of the furnace.

5. In an electric furnace, in combination, a plurality of refractory walls enclosing a furnace chamber, a plurality of relatively narrow refractory members of substantially T-shape supported by said walls, each having an inner end provided with an overhanging flange, stirrups supported by said overhanging flanges, a relatively heavy resistor member supported at spaced-apart points by said stirrups and being self-supporting therebetween, and embodying means on said overhanging flange for preventing movement of said stirrups longitudinally of said resistor member when the same expands and contracts during operation of the furnace.

In testimony whereof, I have hereunto subscribed my name this 10th day of January, 1922.

HOWARD A. HANDS.
